ARMAND H. PEYCKE, OF CHICAGO, ILLINOIS, ASSIGNOR TO AMERICAN STEEL
FOUNDRIES, OF CHICAGO, ILLINOIS, A CORPORATION OF NEW JERSEY.

SUPPORTING MEANS FOR BRAKES.

1,315,396.

Specification of Letters Patent.

Patented Sept. 9, 1919.

Application filed February 13, 1918. Serial No. 217,004.

To all whom it may concern:

Be it known that I, ARMAND H. PEYCKE, a citizen of the United States, and resident of Chicago, in the county of Cook and State 5 of Illinois, have invented certain new and useful Improvements in Supporting Means for Brakes, of which the following is a specification.

This invention relates to supporting means 10 for brakes.

The object of this invention is to improve brake beam supporting mechanism and particularly the coöperative association of the 15 brake beam, safety bar and yieldable member operatively connected thereto.

Generally speaking, this and other objects are accomplished by providing in combination, a brake beam, a safety bar therefor, and an associated resilient member removably 20 locked to one and engaging the other.

The invention is illustrated on the accompanying sheet of drawings in which:

Figure 1 is a fragmentary side elevation, part being in section, of a railway car truck, 25 embodying my invention.

Fig. 2 is an enlarged side elevation of the brake supporting means proper, some of the parts being shown in section, and

Fig. 3 is a fragmentary end view of the arrangement shown in Fig. 2.

The various novel features will be apparent from the following description and drawings and will be particularly pointed out in the appended claims.

The brake mechanism of railway cars must be properly supported and also provision made to prevent the brake beam from falling to the track when disengaged or torn from its normal hangings. Furthermore, it has 35 been found expedient to provide yieldable means for permitting the desirable amount of play of the brake beam during the application and release of the brakes.

By referring to the figures of the drawings, it will be noted that I have shown a railway car truck including a spring plank 45 10, to which hangers 11 are permanently secured, the lower ends of said hangers being provided with aligned openings 12, for the 50 reception of a horizontally extending rigid safety bar 13, the extremities of which extend beyond the outer limit of movement of brake beams 14, which are located above the safety bar 13. The main function of this

underlying safety bar 13 is to catch and retain the brake beams in the event that the same are torn or otherwise accidentally disconnected from their normal hangings to prevent the brake beams from falling upon the tracks, which may result in serious accident.

Interposed between the tension member 15 of the brake beam and the safety bar 13, is a resilient member 16 in the form of an irregular loop. The ends of the resilient member are provided with openings 17 preferably of "I" shape, by means of which the resilient member 16 is mounted or slipped onto the extremities of the safety bar 13, the section of the safety bar and the openings 17 in the ends of the resilient member corresponding to each other. Portions 25 struck up from the metal forming the openings 17, rest upon the upper edge of the safety bar 13. This resilient member preferably after 75 being passed onto the safety bar has one of its ends 18 moved up into a position directly adjacent its associated hanger 11, the other end 19 of the resilient member following accordingly and being retained in such position by a pin 20 passed through the safety bar 13, the pin 20 being locked in position by suitable keys 21. The other end 18 of the resilient member is held in position by a locking member or spring clip 22, which 80 preferably is secured to the safety bar 13, near the associated hanger 11. By referring to Fig. 1, it will be noted that two of these locking members 22 are connected to the safety bar 13 and not only lock the resilient 85 members 16 in position, but also lock the safety bar against longitudinal movement.

The intermediate part of each of the resilient members 16 is provided with a rounded section 23 upon which the diagonally arranged tension member 15 of the brake beam may ride. If desired, collars 24 may be mounted on the tension member for engaging the rounded portion 23 of the resilient member 16. In this way wear of the tension member 15 will be reduced to a minimum.

The resilient member 16 interposed between the brake beam and safety bar acts as a leveling device for the brake beam and not only permits the proper forward and backward movement of the brake beam during the application and releasing action

thereof, but also permits the beam to move vertically during the same breaking and releasing actions.

It is my intention to cover any modifications of the arrangement hereinabove disclosed and which fall within the scope of the invention, as set forth in the following claims.

I claim:

- 10 1. In combination, a brake beam, a safety member therefor, and an interposed resilient member removably locked to one and engaging the other, the resilient member being removable from the member to which it is normally connected by a sliding movement.
- 20 2. In combination, a brake beam, a rigid safety member underlying said beam, and an interposed resilient member removably locked to one and slidably engaging the other, the resilient member being removable from the member to which it is normally connected by a sliding movement.
- 25 3. In combination, a brake beam, a rigid safety bar underlying said beam, and an interposed resilient member removably locked to the safety bar and being in sliding engagement with the beam, said resilient member being slidably removable from said safety bar.
- 30 4. In combination, a brake beam, a rigid safety bar underlying said beam, and a resilient member which may be slipped over the bar and locked thereon and engage the beam.
- 35 5. In combination, a brake beam, a safety bar underlying said beam, resilient means mounted on said bar and engaging said

beam, and means for locking the resilient means on said bar and also locking said bar against movement.

6. In combination, a safety bar, means for supporting the same, means for normally supporting a brake beam mounted on said bar, and means for locking said bar and said brake beam supporting means in position.

7. In combination, a safety bar, a support therefor, brake beam supporting means mounted on said bar, and a member secured to said bar for locking the latter with respect to its support and also locking the beam supporting means in position.

8. In combination, a brake beam, a rigid safety bar underlying said beam, and a looped resilient member removably locked on said bar and being engaged by said beam, said looped member being removable from said bar by a sliding movement.

9. In combination, a brake beam, a safety bar underlying said beam, and a looped resilient member engaged by said beam, the ends of which resilient member being apertured for receiving the safety bar.

10. In combination, a brake beam, a safety bar underlying said beam, a looped resilient member engaged by said beam, the ends of which resilient member are apertured for receiving the safety bar, and means for locking the resilient member to the bar.

Signed at Chicago, Illinois, this 26th day of January, A. D. 1918.

ARMAND H. PEYCKE.
